E. C. PIERCE

HAT SUPPORTING DEVICE

Filed Apr. 9, 1921

Inventor
Elizabeth C. Pierce
By her Attorney
L. George Hause

UNITED STATES PATENT OFFICE.

ELIZABETH C. PIERCE, OF NEW YORK, N. Y.

HAT-SUPPORTING DEVICE.

Application filed April 9, 1921. Serial No. 459,856.

To all whom it may concern:

Be it known that I, ELIZABETH C. PIERCE, a citizen of the United States, residing at New York, in the county and State of New York, have invented certain new and useful Improvements in Hat-Supporting Devices, of which the following is a specification.

This invention relates to a hat supporting device; that is, to a device which may be arranged inside of a hat, particularly a lady's hat, for supporting the hat comfortably upon the wearer's head.

A further object is to provide a device for this purpose which will readily accommodate itself to the contour of the wearer's head and hair thus enabling the hat to assume an easy and proper position irrespective of the way in which the wearer's hair is arranged, and without likelihood of deranging the hair.

A further object is to provide a device which is simple, cheap and efficient and which may be easily and quickly attached in position within a hat.

Other objects and aims of the invention, more or less specific than those referred to above, will be in part obvious and in part pointed out in the course of the following description of the elements, combinations, arrangements of parts and applications of principles constituting the invention, and the scope of protection contemplated will be indicated in the appended claims.

In the accompanying drawings which are to be taken as a part of this specification, and in which I have shown merely a preferred form of embodiment of the invention:

Figure 1 is a perspective view of a lady's hat illustrating the device of this invention in position therein, and

Figure 2 is a perspective view of the device shown enlarged and removed from the hat.

Referring to the drawings for describing in detail the structure which is illustrated therein, the reference character L indicates the hat having the usual head opening 1.

The present invention consists of two

pieces, as 2 and 3, of tape or other similar material, said pieces being of substantially equal length. They extend at right angles to each other and are connected together at their lapping point by a connecting plate G. This plate has two pairs of openings 55 therethru, one pair as 4 and 5, having the tape 2 threaded therethru, and the other pair, as 6 and 7, receiving the tape 3. All of the openings are suitably large so that the plate G is capable of moving readily from one position to another along the length of the two tapes thus enabling the tapes to be positioned for properly fitting to the shape of the wearer's hair.

At their ends both of the pieces of tape are preferably provided with fastening devices H. These may be of any suitable character but preferably consist of double pointed pins since the same are capable of being thrust thru portions of the hat material and 60 of being securely held by being bent over upon the opposite surface of the hat material. The end portions of the tapes are preferably folded back upon themselves, as indicated at 8, so as to provide a suitable attaching body for the devices H.

It should be mentioned that in some instances the ends of the tapes may be left without attaching means, the tapes being in this case intended to be cut to proper lengths 70 for correctly fitting into the hat and to be thereafter attached by needle and thread.

It should also be noted that the attaching devices H, or their equivalent where used, are preferably attached to the tapes in such 75 manner that they may be readily disconnected and moved to other places along the length of the tapes, this provision being for the purpose of enabling the user to properly fit the device into the hat crown.

The position within the hat into which the device is placed is clearly seen in the drawing in Fig. 1; that is, with the ends of the tapes attached at four substantially equidistant points 9 around the hat band, the plate G being held centrally so that it will rest upon the top of the wearer's head and so that the tapes will extend in four radial

directions downwardly about the head to their points of attachment with the hat.

If desired a suitable attaching device may be provided for flexibly connecting the plate 5 G with the crown of the hat so as to insure that the tapes will always stand in the proper position whether the hat is in use or not. This device may take any form but for convenience is shown to consist of a tab 10 connected with the plate G by means of a cord, or the like, 11, said tab being preferably made of gummed cloth or paper so that it is adapted to be stuck on to the inner surface of the hat crown.

15 The tapes 2 and 3 may be of any suitable material but preferably are of the elastic type so that they will stretch longitudinally to a suitable degree for allowing the hat to rest comfortably upon the wearer's head.

20 The use of elastic tape in this connection has a further advantage in that it will stretch and thus permit the hat to be drawn downwardly over the wearer's head to what may be termed an abnormal position. By 25 inserting one or more hat pins in the usual manner at this time thru the hat and hair, then the effort of the elastic tapes to lift the hat will result in clamping the hair to a certain extent between the tapes and the 30 hat pins thus producing a comfortable tightness of the hat upon the head.

While the tapes are shown and described as extending continuously thru the plate G, and said plate G is described as being movable upon said tapes, it should nevertheless be understood that in some instances the 35 tapes may be separated at the plate and that the plate may be connected so that it will not be movable longitudinally of the 40 tapes. It should also be understood that while two pieces of tape, providing four ends, are shown and above described, yet any number of tapes and ends may be provided according to preference, it being ob- 45 served in this connection that the tapes primarily constitute only a sort of false cap which fits readily to the contour of the wearer's hair and which in turn supports the hat.

50 By using this device the band portion of the hat may be suitably large so that it does not press against the wearer's head and de-range her hair. Any ordinary size of hat band may be used with equal comfort pro- 55 vided only that it is large enough not to bind against the wearer's head, and once the device of this invention is placed therein no further attention need be given it during the life of the hat.

60 As many changes could be made in this construction without departing from the scope of the invention as defined in the following claims, it is intended that all matter contained in the above description, or

shown in the accompanying drawings, shall 65 be interpreted as illustrative only and not in a limiting sense.

Having thus described my invention, what I claim as new and desire to secure by Letters Patent is:—

70 1. A hat supporting device comprising a plurality of tapes arranged in lapping position, a connecting plate at the lapping point 75 of said tapes, and said plate having openings therethru thru which said tapes are threaded to hold said tapes connected and suitable for use in the manner set forth.

2. A hat supporting device comprising a plurality of tapes arranged in lapping position, a connecting plate at the lapping point 80 of said tapes, said plate having openings therethru thru which said tapes are threaded to hold said tapes connected, and said openings being of a size to permit free move- 85 ment of the plate longitudinally of said tapes for the purpose set forth.

3. A hat supporting device made up as an article of manufacture adapted to be dis- 90 pensed separately from the hat but to be connected with a hat for use for the purpose set forth, said supporting device comprising a flexible cap adapted to rest upon and to accommodate itself readily to the contour of the wearer's head, and having holding means carried thereby adapted to releas- 95 ably engage the band portion of a hat for releasably retaining the supporting device in operative position within the hat, said holding means comprising a plurality of bendable tangs adapted to penetrate the material of the hat and to be bent into a retaining condition.

4. A hat supporting device made up as an article of manufacture adapted to be dis- 105 pensed separate from the hat but to be connected with a hat for use for the purpose set forth, said supporting device comprising a plurality of flexible cloth tapes connected together radiating from a sub- 110 stantially central point so as to constitute a cap adapted to rest upon and to accom- modate itself readily to the contour of the wearer's head, and attaching means detach- ably connected at the ends of said tapes whereby said attaching means may be 115 moved to different positions along the length of said tapes, said attaching means being of a character to releasably engage the band portion of a hat for releasably retaining the supporting device in operative position 120 within the hat.

5. A hat supporting device made up as an article of manufacture adapted to be dis- 125 pensed separate from the hat but to be connected with a hat for use for the purpose set forth, said supporting device comprising a flexible cap adapted to rest upon and to accommodate itself readily to the contour

of the wearer's head, holding means carried by the cap adapted to releasably engage the band portion of a hat for releasably retaining the supporting device in operative position within the hat, and other means carried by the central portion of said cap by which to connect said central portion with the crown portion of the hat whereby to

support the central portion of the cap suspended from the crown portion of the hat. 10

In testimony whereof I affix my signature in the presence of two witnesses.

ELIZABETH C. PIERCE.
